Blount & Moulton,

ATTORNEYS

UNITED STATES PATENT OFFICE.

JOSIAH DAWSON, OF PHILADELPHIA, PENNSYLVANIA, ASSIGNOR TO THE GLOBE
AUTOMATIC SPRINKLER COMPANY, A CORPORATION OF PENNSYLVANIA.

FUSIBLE STRUT.

1,342,203.

Specification of Letters Patent. Patented June 1, 1920.

Application filed May 24, 1919. Serial No. 299,617.

To all whom it may concern:

Be it known that I, JOSIAH DAWSON, a citizen of the United States, and a resident of the city of Philadelphia, county of Philadelphia, and State of Pennsylvania, have invented certain new and useful Improvements in Fusible Struts, of which the following is a specification, reference being had to the accompanying drawings.

10 The main objects of this invention are to provide an improved fusible strut, of simple and durable construction; to provide a strut adapted for use, preferably, in an automatic sprinkler head; to provide a strut which 15 may be thrown, very suddenly, into operation upon the predetermined rise in temperature; to provide an improved strut which will remain in normal inoperative, but operable, position during very long periods of 20 time without being subject to premature action; to provide in an automatic sprinkler an improved novel and useful strut for retaining the sprinkler in closed condition, and to provide such other improvements as 25 may more fully hereinafter appear.

In the strut and link structures heretofore used in sprinkler heads, it will be found that the strut parts are so constructed that there is a continual tendency to separate the 30 same from the fusible material used to normally maintain them in normally inoperative position. In all of these structures the force tending to separate the strut elements continually acts to shear or tear the fusible 35 material or the solder utilized to bind the parts together, and it frequently occurs that a sprinkler head will operate prematurely due to the action called "creeping" or "cold-flow" of the fusible material. Various structures 40 have been constructed in the attempt to overcome this condition and in the same the principle is to reduce the total force or stress applied to the strut by means of lever arrangements whereby a small component, 45 only, of the total force applied, directly acts upon the parts secured together by the fusible material. In so doing it has been found, however, that the amount of the total force applied must be limited and, moreover, the 50 reduction of such force, through the complicated lever arrangements used, very often act to impede or prevent as quick an operation as might be desired.

My invention, therefore, comprehends the 55 idea of placing the parts of the strut under a much greater compression or stress than

usual whereby the movable elements or parts will have a larger amount of stored elastic energy, which, when the strut operates, gives such parts a more sudden or snappy action, 60 very much in the nature of an explosion.

To accomplish the above mentioned objects and to avoid the above mentioned defects, my invention also comprehends the idea of using a quantity of fusible material 65 normally placed under compression rather than under tension, as has always heretofore been the case. By such an arrangement, wherein the fusible material is under compression, the disadvantages or objections 70 that usually arise under a "creeping" or "cold-flow" action of the fusible material have been totally overcome or avoided. As a consequence, I also have been able to so proportion the leverage of the strut components so that a considerably greater force 75 or a greater component of the total force applied to the strut structure may be utilized with a result of a more sudden and sensitive 80 action of the strut.

In the accompanying drawing in which I illustrate a few embodiments of my invention,

Figure 1 is a vertical elevation of a sprinkler head provided with a strut structure embodying my invention, with a portion of the yoke broken to more clearly show the relation of the parts;

Fig. 2 is a vertical section through the strut arrangement;

Fig. 3 is a top plan view of the strut structure with a portion broken away to more clearly show the relation of the parts;

Fig. 4 is a side elevation of the strut structure showing the position of the parts 95 of the strut when in the act of operating;

Fig. 5 is a vertical elevation of a modification of the strut shown in Figs. 1 to 4 inclusive;

Figs. 6 and 7 are each further modifications of my invention.

Referring now more particularly to the drawing, the strut arrangement, in the preferred form, illustrated in Figs. 1 to 4 inclusive, may be mounted in a sprinkler head 105 structure, of any suitable type, provided with the threaded nipple 1 to an end of which are integrally formed the yokes 2 the latter being formed integrally at the ends thereof with a screw socket 3 through which 110 may be adjustably threaded a compression screw 4. This screw may be provided at

one end thereof with a permanently secured deflector 5 and at the other end thereof with a conical abutment 6. The sprinkler head may be provided with a closure cap 7 upon the top of which may be provided a second conical abutment 8, both of said abutments being coaxial and directed toward each other.

The strut structure comprises an L-shaped member 9 with the limbs 10 and 11 thereof disposed at an angle of substantially 90° with the limb 10 in horizontal and limb 11 in vertical disposition as viewed in Figs. 1 to 4 inclusive. The lower end of the vertical limb 11, adjacent its juncture with the horizontal limb 10, is provided with a conical recess or socket 12 within which the conical abutment 8 of the closure cap 7 is adapted to seat while the upper portion of the limb 11 is laterally bent and is suitably provided at its terminal with a rounded end 13 to form a fulcrum for the obliquely disposed lever 14. The latter is provided at its upper end, beyond the fulcrum point 13, with a conical recess or socket 15 in which the abutment member 6 is adapted to seat. The lower end of the lever 14 contacts with a lateral face of and near one end of a lever member 16 hereinafter more fully described.

The lower or horizontal limb 10 of the angle member 9 is provided at its free end with an upwardly extending flange 17 the upper edge of which is laterally bent and rounded to form a fulcrum for the lever member 16.

Upon the horizontal limb 10 normally rests a thrust member 19 which is adapted to slide horizontally longitudinally over the horizontal surface of the limb 10. This thrust member is provided with an upwardly extending flanged portion 20 between which and the lever portion of the limb 11 may be interposed a quantity of fusible material 21. The lever 16 is suitably bent at the portion 22 to smoothly fit over the fulcrum 18 and is also provided at its lower end with a flanged portion 23 horizontally disposed with relation to the member 10 and with its end 24 in engagement with the end 25 of the thrust member 19. These ends may be tongued and notched whereby lateral relative movement therebetween may be prevented when the parts are in assembled position. The horizontal member 10 may also be provided with an upwardly extending projection 26 which may be suitably formed by indenting the member 10 in any suitable manner. This projection 26 is adapted to fit within an indentation or recess 27 formed in the thrust member 19. By these means, when the parts are assembled, the member 19 may be placed upon the member 10 so that the depression 27 shall register or fit with the projection 26 for the proper locating of said parts and then by

placing the lever 16 so that the tongue 28 of the member 19 will fit within the notch 29 of the lever 16 the latter may be brought to position to fit within the angle formed by the member 10 and the upstanding member 17 with the portion 22 in bearing relation to the fulcrum 18, at which time the fusible material 21 may be applied into place between the flange 20 and the lower portion of member 11. It will be observed that solder or other fusible material also may be placed between the contacting surface of the members 10, 19 and 16 as well as built around the edges thereof in a manner well known in this art. The member 11 also may be suitably ribbed at 30 to strengthen the same, as well as for offsetting the lower end thereof for including the socket 12 in proper relation to the abutment 8. The fusible material may be fused or built into place so as to form an adhering or cohering block between the flange 19 and the member 11.

It will be noted that the fulcrum 13 is located to one side of the line or axis passing through the abutment members 6 and 8 whereby any force applied to the strut structure at the abutments 6 and 8 along the axis thereof will have a tendency to cause the members 11 and 14 to act as a toggle. The force so received by the member 11 is delivered at the fulcrum 13 with the tendency to cause a rotation of the lever 14 about such fulcrum with the end 31 of said lever pressing against the lock lever 16, the upward movement of the lever 14 being normally restrained by reason of its contact with the upper end of said lever member 16. The force applied at the point of contact between the end 31 and the upper end of lever 16 tends to rotate the lever 16 about the fulcrum 18. Such movement is restrained, however, by reason of the thrust member 19 contacting with the end 24 of the lever 16 at one end thereof and abutting against the fusible material 21 at the other end thereof. The tendency of the lever 16 to rotate about the fulcrum 18, which, in the structure as shown in Fig. 1, is clockwise, also tends to cause the end 24 to move toward the left, as viewed in the same figure. This latter tendency of movement acts to horizontally force the member 19 also to the left against the fusible material 21.

It may be seen from the above that when the temperature of the atmosphere in the vicinity of a sprinkler head provided with my improved strut structure, attains a temperature sufficient to melt or fuse the fusible material 21, the force applied through the levers described above will be effective to cause the end of the lever 14 to rotate the lever 16 about the fulcrum 18 with the incidental movement of the end 24 against the end 25 of the thrust member 19 so that the thrust member will move longitudinally

to the left, as viewed in Figs. 1, 2 and 4. Such movement of the latter will first cause such member to rise over the projection 26. The end 24 will be adapted to simultaneously swing upwardly, and to a certain extent, slide over the end 25 to a disengaging position, as is shown in Fig. 4, at which time the end 31 is capable of disengaging from the upper end of the lever 16 and to 10 freely separate therefrom. Until the end 31 disengages from the lever 16 the parts are all under substantially full compression stress and the instant when these parts disengage the elastic energy stored therein acts 15 very suddenly and violently to widely separate and scatter the strut elements.

In the form of device shown in Fig. 5 the arrangement is similar to that shown in Figs. 1 to 4 inclusive, with the exception that 20 the lever arrangement 16' corresponding to 16 of the preferred embodiment is a relatively straight lever with the lower end 24' thereof in lateral abutting contact with the end 25' of the thrust member 19', the latter 25 being, as may be observed, longer than the member 19 of the preferred structure.

In the operation of this device the end 31 of the lever 14 operates to force the upper end of the lever 16' to the right, as shown 30 in Fig. 5, about the fulcrum 18 resulting in a movement of the end 24' to the left, as viewed in Fig. 5, to longitudinally move the member 19' toward the fusible material 21 which upon fusing will permit the movement 35 of the thrust member 19' and the turning of the lever member 16' to permit the end 31 to clear therefrom and the flying apart of the strut elements.

In the form of device shown in Fig. 6, the 40 lever member 14' is provided with a depending end 31' in which is provided a slot 32. Through the latter projects the end 33 of a thrust member 34. The upstanding end 17' instead of being provided with a fulcrum member, corresponding to 18 of the 45 form shown in Figs. 1 and 5 is provided with a slot 35 through which also projects the stem 33 of the member 34. The member 34 is bent so as to inclose therein a rectangular space which may be filled with 50 fusible material 21'. This member 34 also projects vertically through an opening 36 and is provided beneath the horizontal arm 10' of the angle member 9' with a horizontal 55 leg 37 lying adjacent to the under surface of the member 10'. This leg portion may be provided with a projection 38 adapted to normally fit in the aperture 39 provided in the member 10'. This projection 38 is for 60 the purpose of locating the proper position of the member 34 when the parts are being assembled by the mechanic, and also incidentally acts as an outlet for the fusible material when in melted condition.

65 In operation the end 31' of the lever

member 14' presses upwardly against the stem 33 tending to rock or rotate the member 34 about the upper edge 39 of the slot 35 as a fulcrum thereby causing the member 34 to press downwardly upon the fusible 70 material when the latter fuses, the member 34 is adapted to move under the influence of lever 14', the projection 38 having no effect upon such movement. As soon as the member 34 has sufficiently moved to permit the 75 stem 33 to rise to a point where the end 31' can no longer engage the same, the lever 14' will suddenly separate therefrom and the strut parts fly apart.

In the structure shown in Fig. 7 the 80 member 11 is provided with a slot 40 near the lower end of said member through which may horizontally project an end of the thrust member 19''. The other end of this thrust member has an upstanding portion 85 or flange 16'' against which the lower end 31 of the lever 14 laterally presses. The free or projecting end of the thrust member 19'' is provided with an upstanding flange 41 spaced away from the member 11 so as 90 to include therebetween a quantity of fusible material 21''. The lower member 10'' of the strut structure as well as the thrust member 19'' are respectively provided with the indentation projection 42 and recess 43 95 for the purpose of positioning the parts in the assembling thereof in the factory when the fusible block material 21'' is applied.

In operation the end 31 of the lever 14 pressing against the portion 16'' will, upon 100 the fusing of the material 21'', move the member 19'' to the right, as viewed in Fig. 7, to such an extent that as the end is swung upwardly it will clear from the end 16'' and consequently permit the flying apart of the 105 strut arrangement.

While I have shown a preferred embodiment of my invention in Figs. 1 to 4 inclusive, with a few modified structures, as shown in Figs. 5, 6 and 7, I wish it to be understood that I do not consider my invention necessarily limited to the particular details of the devices so illustrated and described by that my invention comprehends all structures, whether struts or links, of any type 110 whatever operating upon the principle of compressing the fusible medium rather than applying a tension or shearing force thereto, prior to or during the operation thereof, as do not depart from the spirit of my invention and the scope of the pending claims:

Having thus disclosed my invention, what I claim and desire to secure by Letters Patent of the United States is:

1. In a fusible strut for sprinkler heads, 125 the combination of a plurality of levers, a thrust member in contact with one of said levers and normally urged to move longitudinally in one direction by said last mentioned lever, a fusible member interposed be- 130

tween said thrust member and another of said levers, whereby said fusible member is normally placed under compression.

2. In a fusible strut comprising an L-shaped member, a lever fulcrumed upon an end of said member, a second lever fulcrumed upon the other end of said member and engaged by said first mentioned lever, a thrust member in contact at an end thereof with said second mentioned lever and fusible material interposed between the other end of said thrust member and said L-shaped member, whereby said first mentioned lever tends to move said second mentioned lever 10 to press said thrust member against said fusible material.

3. In a sprinkler head, the combination of a pair of levers, fulcrumed one upon the other, a third lever operatively connected 20 between the ends of said levers, a thrust member in contact with and adapted to be moved by said last mentioned lever, thermally fusible material between one of said first mentioned levers and said thrust member and placed under compression by said thrust member.

4. In a sprinkler head, the combination of a fusible strut mechanism comprising a plurality of levers, one of said levers normally bearing against a thrust member, fusible material normally restraining the movement of said levers and said thrust member, a positioning projection formed in one of said levers and in said thrust member, whereby 30 relative position of said members may be properly determined in assembling said structures.

5. A strut or link structure comprising

levers placed under an abnormally high stress whereby said levers tend to separate 40 and a restraining means comprising a thrust member longitudinally movable by one of said levers along another of said levers and fusible material placed under compression 45 between said thrust member and said last mentioned lever for normally restraining the separation of said levers.

6. A supporting structure comprising resilient members and a longitudinally movable thrust member placed under abnormally 50 high stress whereby said levers and said thrust member tend to separate, said thrust member provided with a surface of substantial area at one end thereof and a lever engaging portion at the other end thereof 55 and fusible material located between said surface and one of said levers and placed under compression by said levers and said thrust member for normally restraining the separation of said levers and said thrust 60 member.

7. A strut or link structure comprising levers placed under an abnormally high stress whereby said levers tend to separate and a restraining means comprising a thrust 55 member supported by one of said levers and adapted to be moved longitudinally thereof by another of said levers and fusible material placed under compression between 70 said thrust member and one of said levers for normally restraining the separation of said levers.

In witness whereof I hereunto set my hand and seal this 22nd day of May, 1919.

JOSIAH DAWSON.
